UNITED STATES PATENT OFFICE.

JACQUE L. MORGAN, OF KANSAS CITY, MISSOURI.

DESIGN FOR AN INSULATOR.

SPECIFICATION forming part of Design No. 29,782, dated December 6, 1898.

Application filed September 6, 1898. Serial No. 690,386. Term of patent 7 years.

To all whom it may concern:

Be it known that I, JACQUE L. MORGAN, a citizen of the United States, residing at Kansas City, in the county of Jackson and State 5 of Missouri, have invented and produced a new and original Design for Insulators, of which the following is a specification, reference being had to the accompanying drawings, forming part thereof.

10 Figure 1 is a front elevation, and Fig. 2 is a side elevation, of the insulator.

As shown in the drawings, A and A' are the perforations at the upper corners of the insulator.

15 B and B' are the tubes or bushings. F and G indicate the flanges.

C represents the semicircular recess centrally placed between the bushings at the lower side of the insulator.

D and E indicate the horizontal surfaces of 20 the insulator, one above and one below, as shown.

Having described my invention, what I claim as new, and desire to secure by Letters Patent, is—

25 The design for an insulator, as herein shown and described.

JACQUE L. MORGAN.
